UNITED STATES PATENT OFFICE.

FRANCIS LIGHTFOOT, OF LANSDOWNE, PENNSYLVANIA.

RAILROAD-RAIL.

SPECIFICATION forming part of Letters Patent No. 373,591, dated November 22, 1867.

Application filed April 26, 1887. Serial No. 236,135. (No model.)

To all whom it may concern:

Be it known that I, FRANCIS LIGHTFOOT, residing at Lansdowne, in the county of Delaware and State of Pennsylvania, a citizen of the United States, have invented or discovered certain new and useful Improvements in Railroad-Rails, of which improvements the following is a specification.

In the accompanying drawings, which make part of this specification, Figures 1, 2, and 3 are views in side elevation of the two members of my improved rail-joint, showing different forms of construction. Fig. 4 is a transverse sectional view of one of the joints formed by rail ends constructed in accordance with my invention. Fig. 5 is a longitudinal section of a rail-joint formed in accordance with my invention.

The invention herein relates to a class of rail-joints known as the "continuous tread," wherein the adjoining ends of two rails overlap each other; and the invention has for its object as well such a construction of the joint as will effect the locking together of the overlapping ends, so as to prevent independent movement of the members in a vertical direction as to effect continuity of tread; and to this end the invention consists in the construction and combination of parts, substantially as hereinafter more fully described and claimed.

In Letters Patent No. 294,245, granted me February 26, 1884, I have described and claimed a rail-joint formed by overlapping rail ends which have been suitably shaped by swaging or pressing aside the ends of the rails, and at the same time thickening them in the web and elongating the swaged portion, the thickened and elongated ends of adjoining rails being adapted to lap by each other, and thereby form a continuous tread equal in width to that of the rail. Provision was made in that joint for locking the two members as against independent vertical movement by a projection and recess at the ends of the joint, or by a rib along the face of one member and a corresponding recess in the face of the other member. While each form of lock is effective to a certain extent, the projection and recess at the ends of the joints did not form a support for the portions of the joints between them, and hence the bolts which are located along such middle portion are subjected to a

shearing action when a load is placed on that portion of the joint. In the construction having the rib and recess along the entire length of the overlapping faces this shearing action is prevented; but the recess in that position tends to weaken the joint at the point of junction of the body of the rail and the portion pressed aside, as above stated.

In the practice of my invention the ends of the rails are swaged or pressed over to one side of the vertical longitudinal central plane of the rail, so that the head of the end of the rail is reduced about one-half in width, and at the same time the part pressed over is elongated. While being pressed over and elongated the web of the rail is made thicker than the original web by the addition of the metal displaced from the head and flange, as above stated.

The dies by which the above swaging operation is effected are so constructed as to form a rib or ribs, 3, at or near the point of junction of the body 1 of the rail and the tongue 2, formed by the swaging operation. These ribs extend along the inner face of the tongue to a point a little beyond the first bolt-hole, 4, as shown in Figs. 1 and 2, or may extend to a point midway of the length of the tongue, as shown in Fig. 3. Simultaneous with the formation of the ribs 3 grooves 5, corresponding in depth to the projection of the ribs, are formed in the inner face of the tongues at or near the outer ends thereof, said grooves being of a length about half an inch longer than that of the ribs.

In lieu of forming both ribs at or near the inner end of the tongue, a rib and groove may be formed at or near the inner end and a rib and groove at the outer end of the tongue, 90 said parts being oppositely disposed, as shown in Fig. 2; or, if desired, a single central rib may be formed at or near the inner end and a groove at the outer end, as shown in Fig. 3.

In order that the joints may be made by slipping the rails longitudinally, the inner faces of the tongues sliding over each other, the grooves are extended to the ends of the tongue, as shown in Fig. 1; but such construction is not essential, as the grooves may be formed as shown in Figs. 2 and 3, in which case the ribs do not extend to the wall formed by the body of the rail at the inner end of the tongue.

In order to provide a good bearing for the heads and nuts of the clamping-bolts when the latter have been shifted out of perpendicularity with the web of the rail by the longitudinal movement thereof, either in contracting or expanding, I form a longitudinally-convexed seat, 6, around the bolt-holes, the apices of the seats coinciding with the vertical diameters of the holes, as shown in Fig. 5. 5
10 This construction will permit of a bearing at extreme contraction stages of the heads or nuts approximately equal to half the area of the whole bearing-surface of heads and nuts.

The principal characteristic of my invention herein is the formation of a lock extending practically the entire length of the joint without at all impairing the strength of the tongues at their point of junction with the body of the rail, and in the construction shown 15
20 in Fig. 1 the junction of the tongue and body of the rail is re-enforced by the ribs.

I claim herein as my invention—

1. A railroad-rail having its ends swaged or pressed aside, thereby forming a tongue at one 25 side of the longitudinal axis of the rail, said tongue having one or more horizontally-projecting ribs formed on its inner face at or adjacent to the point of junction of the body of the rail and the tongue and extending to or

nearly to the middle thereof, and having one or more grooves or recesses at or near the outer end of the tongue, in combination with an adjoining rail having a similarly-formed end, substantially as set forth.

2. A railroad-rail having its ends swaged or 35 pressed aside, thereby forming a tongue at one side of the longitudinal axis of each end of the rail, the inner face of said tongue being provided with horizontally-projecting ribs extending from the inner end of the tongue to or approximately to a point midway of the length thereof, and grooves extending from a point at or near the end of the rib to the end of the tongue, in combination with an adjoining rail having a similarly-constructed end, substantially 40
45 as set forth.

3. A railroad-rail joint formed by two overlapping rail ends, in combination with clamping-bolts passing through holes in the webs of the rail ends, the portions of the web around the bolt-holes being longitudinally curved, substantially 50 as set forth.

In testimony whereof I have hereunto set my hand.

FRANS. LIGHTFOOT.
